UNITED STATES PATENT OFFICE

JULIAN P. FARNAM, OF MINNEAPOLIS, MINNESOTA, ASSIGNOR TO PAGE & HILL CO.,
OF MINNEAPOLIS, MINNESOTA, A CORPORATION OF MINNESOTA

DESIGN FOR A WIRE LINE POST

Application filed September 8, 1932. Serial No. 44,772. Term of patent 3½ years.

To all whom it may concern:

Be it known that I, JULIAN P. FARNAM, a citizen of the United States, residing at Minneapolis, in the county of Hennepin and State of Minnesota, have invented a new, original, and ornamental Design for a Wire Line Post, of which the following is a specification, reference being had to the accompanying drawing, forming part thereof.

Figure 1 is a front elevation of the wire line post, showing my new design;

Figure 2 is a fragmentary side elevation, on an enlarged scale, the lower portion of the device being broken away for the convenience of illustration; and

Figures 3 and 4 are detail views in section taken on the lines 3—3 and 4—4 of Figure 1, respectively, on an enlarged scale.

I claim:

The ornamental design for a wire line post, as shown and described.

JULIAN P. FARNAM.
